UNITED STATES PATENT OFFICE.

CHARLES S. GRANNIS, OF SYRACUSE, NEW YORK, ASSIGNOR TO NEW PROCESS RAW HIDE COMPANY, OF SYRACUSE, NEW YORK, A CORPORATION OF NEW YORK.

GEAR-GRINDING MACHINE.

1,187,616.

Specification of Letters Patent. Patented June 20, 1916.

Application filed April 4, 1912. Serial No. 688,496.

To all whom it may concern:

Be it known that I, CHARLES S. GRANNIS, of Syracuse, in the county of Onondaga, in the State of New York, have invented 5 new and useful Improvements in Gear-Grinding Machines, of which the following, taken in connection with the accompanying drawings, is a full, clear, and exact description.

10 This invention relates to certain improvements in machines for accurately finishing gear teeth to standard size and form after being cut and hardened in the manner well known to those skilled in the art.

15 The main object of my present invention is to provide means for accurately and uniformly grinding or finishing the previously cut gear teeth to the exact form required for perfect mesh with their companion gears 20 so that they will run silently and smoothly without appreciable lost motion.

Another object is to render the operation 25 of grinding or finishing the teeth of a gear practically automatic after such gear has been properly positioned in the machine and to enable certain parts of the machine to be adjusted to operate with the same degree of accuracy upon gears of different size or pitch.

30 A still further object is to protect the operator from dust and dangers of breakage of the grinding elements by inclosing the latter in a substantially dust-proof housing or protective shield.

35 Another object is to provide simple means for truing the abrasive surfaces of the grinding elements to the required form when worn.

Other objects and uses relating to specific 40 parts of the machine will be brought out in the following description.

In the drawings, Figures 1, 2 and 3 are 45 respectively a top plan, a front elevation and a side elevation of a gear finishing machine embodying the various features of my invention, a portion of the index plate in Fig. 2 being broken away to show the tape drum at the rear thereof. Fig. 4 is an enlarged transverse vertical sectional view 50 through the upper front portion of the machine containing the grinding elements taken on the line 4-4, Fig. 3. Fig. 5 is an enlarged vertical sectional view taken on line 5-5, Fig. 2, showing the means for supporting and operating the spindle upon

which the gear to be ground is mounted. Fig. 6 is a diagrammatic view of the tape and tape drums and coacting parts for rolling the gear along a plane tangential to the pitch circle of the gear, the winding drum being shown in one extreme position by full lines and in its other extreme position by dotted lines. Fig. 7 is a top plan of the gear supporting spindle and carriage showing the edge truing device and gear centering lock and also the tapes, tape drums and index. Figs. 8, 9, 10, 11, 12, 13, 14, 15, 16 and 17 are detail sectional views taken respectively on lines 8-8 and 9-9, Fig. 2; 10-10, Fig. 3; 11-11, Fig. 1; 12-12, Fig. 70 60 65 2; 13-13, Fig. 12; 14-14, 15-15 and 16-16, Fig. 3; and 17-17, Fig. 7.

The various moving parts or mechanisms of the machine are mounted upon a suitable supporting frame which preferably consists 75 of a hollow cast metal base —1— having a rearwardly projecting offset —2— and an upwardly projecting bracket —3— terminating at its upper end in laterally diverging arms —4— for receiving and supporting a 80 pair of oppositely disposed angular brackets or bearing plates —5—. These brackets —5— are disposed in the same transverse vertical plane at opposite sides of the longitudinal center of the machine and are 85 provided with journal bearings —6— for receiving a pair of revoluble shafts or spindles —7— upon which are mounted suitable grinding elements as abrasive disks —8— of carborundum or equivalent material, said 90 brackets being tiltable laterally for varying the angle of the disks and their supporting shafts as may be required in grinding gears of different pitch or different forms of teeth. For this purpose, the upper ends 95 of the brackets are pivotally secured by bolts —5— to the front faces of their corresponding arms —4— in approximately the same horizontal plane as the central portion of the spindles —7—, while their lower 100 ends extend downwardly some distance below said spindles and are concentric with the axes of their pivots and slidable along concentric bearings or guides —9—, having suitable graduations to indicate the angle 105 or pitch to which the spindles and their grinding disks may be adjusted.

The portions of the brackets just above their lower concentric edges are provided with laterally elongated slots —10— also 110

concentric with said pivots for receiving clamping bolts —11— which are tapped into the adjacent portions of the arms —4— for holding the brackets in their adjusted positions.

5 Each bracket is preferably provided with a pair of journal bearings —6— spaced a sufficient distance apart to receive between them suitable pulleys —12— which are secured to the central portions of the shafts or spindles —7— and adapted to be connected by belts —13— to corresponding pulleys —14— on the upper end of an upright rocking frame —15—. This frame —15— is secured at its lower end to a rock shaft —16— which extends transversely of the machine and is journaled in suitable bearings —17— on the rearward extension —2— of the base —1— so as to allow the upper end of the frame —15— carrying the pulleys —14— to be adjusted forwardly and rearwardly for tightening the belt. This adjustment may be effected by any suitable means consisting, in this instance, of a pair 10 of sectional rods —18— having their rear ends pivotally connected at —19— to the upper portion of the frame —15— and their front ends similarly connected by pivotal bolts —20— to brackets —21— on the arms —4—, the sections of each rod being connected by a turn buckle —22— which is held in its adjusted position by lock nuts —23— as shown more clearly in Figs. 1 and 3.

15 The upper portions of the brackets —5— and arms —4— are provided with laterally elongated registering openings —24— aligned with the lower side of the pulleys —12— for permitting the passage of the lower sides of the belts —13— therethrough, said openings being also concentric with the pivotal bolts —8— which are located directly at the rear of the center of the pulleys so as to allow the brackets —5— to be adjusted laterally without throwing the pulleys —12— out of alignment with the companion pulleys —14—.

20 The bearings —6— are provided with sleeve linings —25— of phosphor bronze or equivalent material in which the spindles —7— are directly journaled, said sleeves being held in the bearings —6— against relative rotation or axial movement by one or more set screws —26— as shown more clearly in Fig. 2.

25 The outer ends of the spindles —7— are reduced in diameter to form annular shoulders and for receiving suitable collars —27— which are secured to said reduced portions by set screws —28— with their inner ends spaced apart from the annular shoulders for receiving interposed portions of independently revoluble adjusting sleeves —29— and anti-friction end thrust ball bearings whereby the spindle and sleeve are held against relative endwise movement, and

at the same time permitting the sleeves to be adjusted rotarily relatively to their respective spindles.

30 The inner ends of these sleeves —29— are provided with external threads engaging internal threads in the adjacent ends of the stationary bearing sleeves —25— for adjusting the spindles —7— and disks —8— carried thereby axially in grinding gears of different pitch.

35 The outer ends of the adjusting sleeves —29— are provided with inwardly projecting tapering flanges fitting closely upon the peripheries of the adjacent ends of the stationary bearing sleeves —25— and provided 40 with graduations upon their peripheries coacting with a fixed indicator on the bearing sleeves for indicating the degree of axial adjustment of the spindles and disks.

45 The bearing sleeves —25— are preferably 45 divided or split through one side in line with the set screws —26—, the inner ends of which are tapered and threaded and engaged with corresponding tapered openings in the sleeve registering with the longitudinal slits so that when the set screws are tightened, they expand the sleeve against the inner faces of the outer bearings —6—, the latter being also divided through one side and drawn together by bolts upon the 50 inner sleeves, thereby affording a simple but easily accessible means for adjusting the bearings to the spindle to take up wear if necessary.

55 Each spindle adjusting sleeve —29— is 55 frictionally held against accidental rotation when once adjusted by means of one or more, in this instance four, friction pins —30— which are mounted with an easy sliding fit in axially extending sockets in the 60 adjacent ends of the bearing sleeves —25— and are spring pressed into engagement with the inner ends of the spindle adjusting sleeves —29— by coiled springs —31— interposed between the ends of the sockets and 65 the inner ends of the pins.

70 The abrasive disks —8— are rigidly clamped to the inner ends of their respective spindles —7— by means of clamping collars —32— and —33—, the collars —32— 75 being provided with central tapering bores fitting with a snug friction fit upon the inner tapering ends of their spindles —7— and are frictionally held in operative position by nuts —34— which engage the inner 80 reduced threaded ends of said spindles.

75 The clamping collars or rings —33— are mounted upon reduced concentric portions on the inner ends of their companion collars —32— and are secured thereto by clamping bolts —35— as best seen in Fig. 4, leaving an intervening annular space between the marginal edges of the collars of each pair between which the hubs of the abrasive disks 85 together with suitable packing washers are 90

firmly clamped, the packing washers serving to prevent breakage of the disk by direct contact with the metal collars when tightening the latter upon the hub of the disk.

5 The marginal edges of the grinding disks —8— which are utilized for grinding or finishing the teeth to the desired form are beveled so that their inner and outer faces are disposed at an angle corresponding to 10 the angle of inclination of the spindles from a horizontal line, in this instance, twenty degrees, the outer grinding faces of the disks being disposed at right angles to the axes of their respective spindles and therefore 15 the inner adjacent faces are parallel which permits the adjacent faces of the disks to be brought into close juxtaposition.

The thickness of the beveled edges of each disk is slightly less than half the width of 20 the space between the teeth of the gear which is being ground so as to allow the grinding edges of both disks to readily enter the space at the root of adjacent gear teeth to give the desired width to such space according 25 to the pitch of the gear, such width being regulated to a nicety by adjusting the spindles and their disks axially through the medium of the micrometer adjusting sleeves —29—, or if desired the disks may 30 be adjusted a sufficient distance apart to receive one of the gear teeth between them so that their outer grinding surfaces may operate upon the sides of alternate teeth which face each other as shown in Fig. 4.

35 The grinding disks are inclosed within a suitable dust proof housing —36— which is preferably divided vertically in the plane of the axes of the spindles —7— forming front and rear half sections, one of which, 40 as the rear section, is secured by bolts —37— to the upper ends of the arms —4— of the standard —3—, the other section being secured by bolts —38— to the first named section. This housing not only protects the 45 operator against flying dust but also against injury in case the disks should break, it being understood that these disks are driven at comparatively high speed, and for this purpose the pulleys —14— are secured to a 50 horizontal shaft —16— which is journaled in bearings —17— on the upper end of the frame —15— and is provided with a tight pulley —14— adapted to be connected by a belt to any available source of power not 55 shown.

The lower side of the shield or housing —36— is provided with an opening sufficiently large to permit a relatively small portion of the lower sides of the grinding 60 disks —8— to protrude therethrough and also to permit the gear to be brought in contact with said disks even though the diameters of the latter may be reduced by wear and repeated truing.

65 *Disk truing mechanisms.*—As previously

intimated, it is necessary to keep the grinding faces of the disks at the proper angle or at right angles to their respective axes and for this purpose I have provided the machine with a pair of surface truing devices one for each disk, each device consisting of a diamond-point cutting tool or pin —40— mounted on the upper end of a rock arm —41— having its lower end pivoted at —42— to a rock shaft or spindle —43— which is journaled in a suitable bearing —44— on the adjacent side of the lower front portion of the shield or housing —36—, each rock shaft —43— and cutting tool —40— being disposed in lines substantially parallel with the axis of the corresponding disk —8— so that when the rock arm —41— is moved back and forth about the axis of the rock shaft —43—, the cutting point of the tool will be moved at substantially right angles to the axis of the disk or parallel and in contact with the grinding face of said disk.

The cutting tool —40— is movable endwise toward and from the grinding face of its disk within a suitable bearing —45— which is rigidly clamped in the upper end of the rock arm —41—, said cutting tool being held against rotation within said sleeve by means of a key —46— which rides in a lengthwise key-way in the interior of said sleeve as the cutting tool is adjusted endwise.

Each cutting tool is adjusted endwise by means of a rotary hand-operated sleeve 100 —47— journaled upon a reduced outer end of the cutting tool between a shoulder —48— and nut —49— by which the adjusting sleeve —47— is held against relative endwise movement on the cutting tool.

The hub of the sleeve —47— is threaded externally and engaged with internal threads upon the adjacent end of the relatively stationary sleeve —45— so that by rotating the adjusting sleeve —47—, it will 110 be screwed inward or outward according to the direction of rotation, thereby imparting similar endwise motion to the cutting tool to bring the cutting point into and out of contact with the grinding surface of the 115 disk.

The sleeve —47— is provided with an inwardly projecting flange —50— telescoping with the adjacent end of the sleeve —45— and is preferably tapered and provided with 120 graduations coacting with an index on the periphery of the sleeve —45— to accurately determine the degree of endwise adjustment of the cutting tool.

The means for adjusting the cutting tool 125 must necessarily be located outside of the shield or housing —36—, while the cutting tool must extend into the housing in order to contact with the grinding face of the disk and for this purpose the side of the shield 130

adjacent the cutting tool is cut away at —52— radially and axially of the disks to allow the bearing in which the cutting tool is mounted to play therein. When the cutting tool is adjusted endwise into proper cutting contact with the grinding faces of the disk by means of the adjusting sleeve —47—, the rock arm —41— is moved about the axis of its supporting shaft —43—, the upper end of said rock arm being guided in suitable ways —54— concentric with the axis of the shaft or spindle —43— so as to hold the cutting tool in exact parallelism with the grinding face of the disk in all positions of adjustment of the rock arm —41—, said guides —54— also serving to hold the cutting tools and rock arms against undue vibration or chattering.

When the angle or the inclination of the disks and their supporting shafts or spindles are changed for finishing the teeth of gears of widely varying pitch, it is necessary to adjust the cutting tools to conform to the adjustment of the disks and for this purpose the lower end of the rock arm —41— is adjustable along and upon the rock shaft —43— by providing said shaft with a series of apertures —56— arranged at different points in its axis for receiving the pivotal pin —42—.

It is now clear that aside from the fact that the grinding faces of the disks are previously formed or adjusted so as to travel in planes approximately tangential to the involute curves of the teeth of gears of predetermined pitch, said grinding faces may be trued and kept at the proper angle by means of the cutting tools —40— and their adjusting device.

40 The rock arms —41— are adapted to be operated by hand to move their respective cutting tools —40— across the grinding faces of their respective disks but are returned to their normal starting positions to bring the cutting tools out of contact with the disks by suitable plungers —57— having their front ends bearing against the rear edges of the arms —41— and their rear ends slideable in suitable bearings —58— on the adjacent sides of the shield or housing —36— and are spring pressed forwardly by coiled springs —59— within the bearings —58—, the upper ends of the rock arms —41— normally resting against a limiting stop —60— on the front ends of the guides —54—.

In addition to the truing devices just described for keeping the outer faces of the grinding disks in planes at right angles to their respective axes, I provide suitable means for truing the peripheries of the disks and keeping them both of the same diameter, said means consisting of a vertically disposed diamond point cutting tool —61— adjustable vertically in a suitable holder —62— which in turn is adjustable horizontally in

a bearing —63— on a transversely movable carriage —64—, the cutting tool —61— being held in its adjusted position by a clamping bolt —65—, while the holder —62— is held in its adjusted position by a clamping bolt —66— in the bearing —63—.

The cutting points of the tools —40— for truing the outer grinding faces of the disks —8— are always disposed in a plane co-incident with said grinding faces ready for use at any time, while the point of the cutting tool —61— for truing the edges or peripheries of the disks is always located in the horizontal plane of the lowermost portions of the peripheries of said disks but normally to one side thereof and some distance in front of the gear when the latter is in position for grinding or finishing but may be moved rearwardly and laterally into position for truing the periphery of the disks by manipulating the carriage —64— in a manner hereinafter described.

Gear supporting and operating mechanism.—In order that the teeth of the gear as —a— may be ground or finished to the desired involute form and size, suitable means is provided for bringing the gear and grinder into perfect mesh with each other with the abrasive faces approximately tangential to the involute curves of the teeth with which they are adapted to contact, additional means being provided for reciprocating the gear transversely of its axis with its pitch circle in rolling coincidence with and along a tangent thereto at right angles to a medial plane between the abrasive faces. For these purposes the carriage —64— carrying a gear supporting spindle —67— is disposed in a plane some distance below the lower edges of the grinding disks and is operable axially thereof across and upon a forwardly and rearwardly movable bed —68— which in turn is supported upon a vertically movable cross head —69—, the latter being guided on upright ways —70— on the front side of the standard —3— as shown more clearly in Figs. 2 and 3, thereby permitting the gear supporting spindle to be moved horizontally in planes at right angles to each other across the lower grinding face of the disks and also vertically to and from the disks for purposes hereinafter more fully described.

The spindle —67— is journaled in suitable bearings —71— on the carriage —64— at right angles to the vertical plane of the axes of the grinding disks —8— so as to extend forwardly and rearwardly of the machine in a plane some distance below the lower edges of said disks, the rear end thereof being reduced and tapered for receiving a split friction sleeve —72— which is adapted to receive and support the gear —a—, the teeth of which are to be ground or finished. After these gears are hardened,

their central bores are accurately ground to the desired gage and are adapted to be frictionally held upon the sleeve —72— by expanding the latter in the bore and for this purpose I have provided a cap screw —73— which is tapped into the rear end of the tapered portion of the spindle and when screwed up tightly, engages the adjacent end of the sleeve —72— and wedges it tightly upon the tapering portion of the spindle, thereby tightening it in the bore of the gear.

10 The portion of the spindle in front of the sleeve —72— is threaded at —74— for receiving a nut —75— whereby the sleeve with the gear thereon may be easily and quickly loosened and removed axially by simply rotating the nut through the medium of a spanning wrench or equivalent tool 15 adapted to be inserted in sockets in the periphery of the nut.

20 The front end of the gear supporting spindle —67— extends forwardly some distance beyond its bearing —71— for receiving and supporting a tape drum —76— and an index plate —77—, the latter having a forwardly projecting hub upon which is frictionally clamped a radially projecting arm —78— for a purpose presently described.

25 The tape drum —76— is loosely mounted on the spindle —67— and is provided with circular bearings of exactly the same diameter as the pitch diameter of the gear to be ground, and to the peripheries of these bearings are attached one end of a pair of oppositely wound steel tapes —79— drawn tightly thereon and having their opposite ends attached to the peripheries of some 30 what smaller drums —80— on opposite sides of the machine. These smaller drums —80— are journaled in suitable bearings —81— on upright brackets —82— rising from the bed —68— some distance to opposite sides of the spindle —67—, said drums —80— having their upper sides disposed in substantially the same horizontal plane as the upper side of the peripheries of the drums —76— so as to hold the tapes —79— 35 in the same horizontal plane tangential to the pitch circle of the gear for the purpose of imparting rolling motion to the gear and its supporting spindle as the carriage —64— is reciprocated transversely of the machine.

40 The drum —76— is provided with coaxial circular bearings arranged side by side in close proximity and of the same diameter as that of the pitch circle of the gear and upon which the inner ends of the tapes are wound in opposite directions and secured thereto in any well known manner.

45 The outer ends of the tapes are rigidly secured by suitable fastening means to the peripheries of the drums —80— which are

aligned with the corresponding circular bearings of the drum —76— and adjustable rotarily to draw the tapes tightly in a plane tangential to the pitch circle of the gear. For this purpose the spindles as —83— to 50 which the drums —80— are secured are provided with worm gears —84— rigid thereon and engaged by suitable worms —85—. These worms are mounted upon separate shafts or spindles —86— which are journaled in the bearings —81— at right angles to the spindles —83— and extend outwardly beyond said bearings for receiving a suitable operating member —87— and friction disks —88— and —89—.

55 The operating member —87— preferably consists of a hand wheel having a radial web loosely journaled upon the spindle —86— and frictionally held between the friction disks —88— and —89—, the disk —88— being secured to the spindle —86—, while the disk —89— is mounted upon an angular portion —90— of said spindle and is adjustable axially by means of a nut —91— so as to increase the friction upon the disk —87— when necessary. The object of this slip friction connection between the operating member —87— and spindle —86— is to prevent excessive stretching or breaking of the tapes during the tightening 60 adjustment, and at the same time the worm and gear affords a positive lock to hold the tapes in their tightened condition.

65 It is now apparent that when the gear is properly adjusted or centered for grinding 100 coaction with the grinding disks —8— and the carriage —64— reciprocated, the tapes —79— operating upon the drum —76— will cause the gear to roll along the plane of the tapes tangent to its pitch circle in substantially the same manner as though it were in mesh with a fixed toothed rack, thereby causing the teeth of the gears to be ground in involute curves of standard form and size.

70 The movement of the carriage —64— is sufficiently slow to effect the proper grinding of the set of teeth which may be in contact with the grinder during one complete cycle of movement of the carriage from one extreme position to the other and return and after each cycle of operation upon one set of teeth, the gear supporting spindle and gear thereon is shifted rotarily one tooth space to permit the grinding disks to act upon another adjacent set and so on until all 75 of the teeth of the gear are ground to the desired form and size. For this purpose, the circular index plate —77— is rigidly secured to the reduced front end of the gear supporting spindle —67— by means of a set 125 screw —92— and has its periphery provided with a series of notches —93— corresponding in number to the number of teeth of the gear to be ground and for interlocking engagement with a suitable pawl —94— which 130

is pivotally mounted upon a radially projecting arm —95— on the front face of the drum —76— as shown more clearly in Figs. 2, 6 and 7 for locking the tape drum —76— to the index plate and therefore to the gear supporting spindle —67— during the grinding operation upon each set of teeth.

After each grinding operation upon one set of teeth, the gear is rotarily shifted one tooth space to cause successive grinding of the remaining teeth and in order to accomplish this result, a tripping pawl —96— is pivoted to the stationary cross bar —97— on the upper ends of the standards —82— to swing in the direction of movement of the carriage —64— and having its lower end projecting into the path of a suitable lug —98— on the pawl —94— so as to trip said pawl from interlocking engagement with the index plate —77— when the carriage —64— approaches the limit of its starting position or just before the gear reaches the position shown by dotted lines in Fig. 6, it being understood that as the carriage and gear supporting spindle mounted thereon are moved in one direction, said spindle and parts carried thereby are rotated in the opposite direction by means of the tapes —79— so that as the carriage approaches the limit of its return movement, or to the right of Fig. 6, the pawl —94— will be moved bodily to the left of said figure from the position shown by dotted lines until it is engaged and tripped by the tripping pawl —96— which is held against movement in one direction by contact with a shoulder —99— on the bar —97—.

Just before the pawl —94— is forced from its locking position by contact of the lug —98— with the tripping pawl —96—, the radial arm —78— is brought into contact with a fixed stop —100— on the bracket —82— at the right of Figs. 2, 6 and 7 and as the carriage continues its return movement, the pawl —94— will be carried slightly beyond the tripping pawl —96— to the position shown by dotted lines in Fig. 6 and thereby released and at the same time the index plate will be held against rotation by the stop —100— until the pawl —94— is forced by a spring —94'— into the next succeeding notch —93— of the index plate to again lock the drum —76— to the spindle, this additional movement of the carriage after the pawl has been released being sufficient to shift the gear rotarily one tooth space and during such additional movement the radial arm —92— simply slides along the limiting stop —100—.

With the gear now in its starting position for grinding another set of teeth as shown by dotted lines in Fig. 6, the movement of the carriage —64— to the left causes the tapes —79— to roll the gear to the

right along the tangent of its pitch circle coincident with said tape, thereby rocking the arm —92— downwardly and to the left until it encounters a limiting stop —101— which is mounted upon an adjustable bar —102— on the front of the forwardly and rearwardly movable carriage —68—, thereby causing said arm —92— to turn upon the hub of the index plate —76— which together with the spindle supporting gear continues to rotate to the right until the carriage is moved to its extreme forward position to the left a sufficient distance to grind the gear tooth from its root to its point as shown by full lines in Fig. 6.

The object in limiting the movement of the arm —92— by the stop —101— is to keep said arm in proper position for contact with the limiting stop —100— at the proper time according to the number of teeth of the gear, said stop —101— being adjustable to limit the movement of the arm —92— at different points as may be required in grinding gears of different numbers of teeth. This movement of the carriage —64— to the left from its starting position causes the pawl —94— to travel to the right against the tripping pawl —96— which is free to move to the right out of the path of the shoulder —98—, thereby permitting the pawl —94— to remain in locking engagement with the index plate during the movement of the carriage —64— to its extreme left-hand position and return until the pawl —94— is again tripped on the return in the manner previously described.

In placing the gear —a— upon its supporting spindle —67— it may be centered to bring its teeth in proper registration with the grinding disks by means of a centering or locking bolt —103— which is slidably mounted radially of the gear and its supporting spindle upon a suitable support —104— and is adapted to be spring pressed into the space between the teeth of a gear by means of a coiled spring —105— interposed between a shoulder on the locking bolt and the end of the socket in which the bolt is slid able, said bolt being also provided with a radially projecting pin —106— movable in a slot —107— in the outer end of the bearing in which the bolt is movable and is adapted to be turned with the bolt to engage the end face of said bearing to hold the bolt out of interlocking engagement with the gear teeth during the grinding operation, the outer end of the bolt being provided with a hand piece —108— by which it may be withdrawn endwise against the action of the spring —104— and turned so as to move the pin —106— into and out of registration with its slot —107—. The support —105— upon which this centering bolt is mounted may also be adjusted transversely of the axis of the gear and its supporting

spindle along a suitable way —109— on the carriage —64— and held in its adjusted position by a clamping bolt —110— as shown more clearly in Fig. 7, the object of such adjustment being to properly position the centering bolt —103— for gears of different size.

In the initial adjustment of the machine for grinding a greater or less number of 10 gears of the same size, the carriage —64— is adjusted to the right in such a position as will bring the lug —98— on the pawl —94— at some point between the limit of its movement to the right and its tripping 15 position with one of the toothed spaces of the gear in registration with the centering bolt —103— whereupon said bolt is released to enter such space and suitable means provided for determining the exact position of 20 the carriage —64— while the gear is still held by the centering bolt, and for this purpose I have provided the forwardly and rearwardly movable bed —68— with an upwardly projecting arm —111— in which is 25 mounted an adjusting screw —112— held in place by a lock nut —113— so that its inner end forms an abutment in line with the adjacent end of the carriage. Between this abutment and adjacent end of the carriage 30 is fitted a gage block —114— which has been previously made to the width corresponding to the distance between the carriage and abutment when the centering pin is engaged with the gear in the manner previously 35 described, leaving sufficient clearance between said carriage and abutment when the gage block is removed to permit the return of the carriage to its starting position to trip the pawl —94— and shift it into engagement 40 with the next succeeding notch of the index plate —77— after the centering pin has been withdrawn from engagement with the gear. In other words during the grinding operation, the locking bolt —103— is withdrawn and locked in its inoperative position 45 and the gage block —114— is also withdrawn and laid aside to permit the carriage —64— to be reciprocated from one extreme to the other of its movement as determined 50 by the position of the connecting rod —139— on the crank disk —137—.

After the teeth of each gear have been properly ground and the gear removed from the spindle, the gage block —114— is placed 55 in operative position between the abutment —112— and adjacent end of the carriage which is adjusted to abut against the inner end of the gage block when the latter is in contact with the abutment, whereupon another gear to be ground is placed upon the spindle and centered by the locking bolt —103—, the gear being then tightened upon the spindle by adjusting the bolt —73— whereupon the centering bolt —103— is 60 withdrawn and locked in its inoperative position

sition and the gage block —114— removed and the machine then set in operation with the assurance that the teeth of the gear —a— will be ground to standard form and size by the grinding elements.

The carriage —64— is preferably reciprocated by a mechanism driven by the shaft —16— on the upper end of the rocking frame —15— and for this purpose I have provided one end of said shaft with cone 75 pulleys —116— adapted to be connected by a belt —117— to another set of cone pulleys —118— on an underlying shaft —119— which is also journaled in suitable bearings upon the rocking frame —15— as shown 80 more clearly in Figs. 1, 2 and 3.

Secured to the opposite or left-hand end of the shaft —119— is a spiral gear —120— meshing with a superposed spiral gear —121— which is mounted upon one end of 85 a flexible shaft —122—, the latter being journaled in a gear case —123— inclosing the gears —120— and —121— and to the adjacent end of the flexible shaft —122—. This flexible shaft —122— extends forwardly and has its front end telescoping 90 within and keyed to an axially movable rotary sleeve —124— as shown more clearly in Fig. 9, said sleeve being journaled in a suitable bearing or gear case —125— on the 95 left-hand side of the vertically movable cross head —69— as seen in Figs. 2 and 3.

The front end of the sleeve —124— is provided with a clutch section —126— movable into and out of engagement with a corresponding clutch section —127— on the adjacent end of a coaxial worm —128— which is journaled in a suitable bearing —129— in the gear case —125— and meshes with a worm gear —130— also mounted within 100 105 said gear case.

The opposite or rear end of the clutch sleeve —124— is provided with an annular groove —131— for receiving an eccentric bearing —132— on the inner end of a rotary spindle —133—, said spindle being journaled in a bearing —134— in the gear case —125— and is provided at its outer end with a hand piece or knob —135— by which the eccentric —132— may be operated 110 115 to shift the sleeve —124— axially and thereby throw the clutch —126— into and out of engagement with its companion clutch section 127.

The worm gear —130— is secured to an 120 upright shaft —136— which is also journaled in the gear case —125— as shown more clearly in Fig. 8 and is provided at its upper end with a cam disk or eccentric —137— having a radial slot —138— in 125 which is adjustably secured a pivotal bolt —139— for receiving the adjacent end of a connecting rod —140—. The opposite end of this rod —140— is pivotally connected at 130 —141— to the carriage —64— for recipro-

cating said carriage as the disk —137— is rotated, the connections between the connecting rod —140— and disk —137— being adjusted so as to impart the desired degree 5 of movement to the carriage.

The carriage —64— is connected to the rod —140— in such manner as to cause the carriage to move a greater distance to the right-hand side of the grinding disks than 10 to the opposite side so as to provide for the extra movement required to shift the gear rotarily one tooth space at each return of the carriage to its starting position as previously pointed out.

15 It is sometimes necessary to move the carriage voluntarily instead of automatically and for this purpose the shaft or spindle —136— is extended downwardly some distance below the worm gear —130— for re-

20 ceiving a bevel gear —142— and a clutch member —143—, the latter being spring pressed into engagement with a coacting clutch section —144— on the lower end of the hub of the gear —130— as shown more 25 clearly in Fig. 8.

The sleeve —143— is locked to the hub of the bevel gear —142— by dowel pins —145—, said dowels entering sockets in the sleeve —143— which also receive springs 30 —146— for holding the clutch sleeve —143— in engagement with the clutch section —144—.

The bevel gear —142— meshes with a pinion —147— on the rear end of a forwardly 35 projecting spindle —148— which is journaled in a suitable bearing —149— on the gear case —125—, the front end of the spindle being angular in cross section for receiving a hand crank or other suitable tool by 40 which the spindle —136— may be rotated to reciprocate the carriage through the medium of the clutch sleeve —143— and gears —142— and —147—.

45 As previously stated, the carriage —68— is movable forwardly and rearwardly and is also adapted to be raised and lowered to enable the gears to be placed on the spindle, while the grinding elements are revolving and for this purpose, the carriage —68— is 50 provided on its lower side with a toothed rack —150— meshing with a worm —151—, the latter being secured to a forwardly and rearwardly extending shaft —152— which is journaled in suitable bearings on the vertically 55 movable cross head —69— and its front end is preferably angular in cross section for receiving a suitable crank or equivalent tool by which this forward and rearward adjustment of the carriage —68— and gear 60 supporting spindle may be affected voluntarily.

The means for adjusting the cross head —69— vertically consists of a diagonally disposed horizontal shaft —153— journaled

in a suitable bearing —154— on the cross head —69— and having its inner end provided with a bevel gear —155— meshing with a similar but larger bevel gear —156— on an upright shaft —157—, the front end of the shaft —153— being angular in cross 70 section for the reception of a suitable crank or equivalent tool by which the upright shaft —157— may be rotated at will. The upper end of this shaft —157— is journaled in a suitable bearing —158— in the cross head —69— and its lower end is screw-threaded at —159— and engaged with an internally threaded sleeve or hub —160— in the top of the base —1— of the main supporting frame so that as this shaft is rotated the cross head and parts carried thereby will be raised or lowered according to the direction of such rotation.

The operation of my invention has been fully set forth in the foregoing description 85 and although I have described one particular construction for carrying out the various objects, it is evident that the details of such construction may be varied materially without departing from the spirit of my invention and therefore I do not limit myself to the exact construction shown and described.

What I claim is:

1. In a gear grinding machine, a supporting spindle for a gear blank, means for reciprocating said spindle radially in parallelism with its axis, additional means co-acting with the first named means for rotating the spindle, and thus imparting a rolling motion to the gear blank along a plane tangential to the pitch circle of the gear and parallel to the plane of movement of the spindle, a pair of rotary grinding disks having their active edges intersecting said 90 plane, and means for rotating said disks.

2. In a machine for finishing gear teeth, a pair of rotary grinding disks having opposite faces disposed in planes converging toward the periphery at one side, said grinder 100 having parallel grinding faces spaced apart at the grinding point to enter different tooth spaces of a gear, means for rolling a gear along a tangent to its pitch circle and at right angles to a medial plane between 110 said faces, and additional means for adjusting the gear into and out of mesh with the grinder.

3. In a machine for grinding gear teeth, a pair of rotary spindles disposed end to end at an angle to each other, circular grinders carried by the spindles, means for adjusting the spindles and their grinders axially, rotary means for supporting a gear with its pitch circle intersecting the peripheries of 120 the grinders, additional means for moving the gear supporting means at right angles to a medial plane between the grinders, and 125

further means for rotating the spindle to roll the gear along a tangent of its pitch circle at right angles to such plane.

4. In a machine for grinding and finishing the teeth of gears, a pair of rotary grinder-supports, means for adjusting said supports to different angles relative to each other, separate means for adjusting the supports axially, a rotary gear-support adjustable to bring the pitch circle of the gear within the periphery of the grinders, a drum coaxial with the gear-support and having a circular bearing of the same diameter as that of the pitch circle of the gear 10 to be ground, flexible members having one end wound in opposite directions around and upon said bearings and their opposite ends extending in the same tangent therefrom and at right angles to a medial plane 15 between the grinders, holding means for said opposite ends of the members, and means for moving the gear support and drum parallel with said tangent.

5. A gear grinding machine having a rotary grinder and means for rolling a gear along a tangent of its pitch circle transversely of and in mesh with the periphery of the grinder, said means including a drum having a circular bearing of the same radius as that of the pitch circle of the gear 20 to be ground, and a flexible member wound thereon and extending tangentially therefrom.

6. A machine for finishing gear teeth comprising separate axially adjustable rotary grinding disks, a mechanism for reciprocating a gear transversely of its axis and imparting to it a rolling motion along a plane tangential to its pitch circle.

40 7. A machine for finishing gear teeth having means for rolling a gear along a plane tangent to its pitch circle, said means comprising circular bearing members co-

axial with and of the same radius as the pitch circle of the gear, and tapes oppositely wound on said bearing members,

8. In a machine for finishing gear teeth, a rotary gear-supporting spindle having circular tape-receiving faces concentric therewith and of the same radius as the pitch circle of the gear, tapes wound at one end upon said surface, separate device for holding the opposite ends of the tapes, means for reciprocating the gear-supporting spindle in a straight line at right angles to its axis, and 50 a rotary grinder having its periphery cutting through the pitch circle of the gear.

9. In a machine for finishing gear teeth, a rotary gear-supporting spindle, means for moving the spindle axially, separate means 60 for reciprocating the spindle radially in a straight line, additional means for imparting a rotary motion to the spindle at such speed as would impart a rolling motion to the gear along a plane tangent to its circle 65 and parallel with the reciprocatory movement, additional means for adjusting the spindle in a plane at right angles to its reciprocatory movement, and rotary grinding disks having its periphery traveling through 70 the pitch circle of the gear.

10. In a machine for finishing gear teeth, a gear-supporting spindle, means for reciprocating the spindle radially in a straight line, additional means for rotating the spindle in opposite directions as it is reciprocated, a grinder meshing with the teeth of the gear for engaging and centering a gear upon the spindle to bring its teeth into proper registration with the grinder. 75

In witness whereof I have hereunto set my hand on this 30th day of March, 1912.

CHARLES S. GRANNIS.
